UNITED STATES PATENT OFFICE.

JOHN W. OLIVER, OF NEW YORK, N. Y., AND HENRY BRUCKER, OF NEWARK, NEW JERSEY.

THREAD GUIDE AND SUPPORT.

1,387,300.

Specification of Letters Patent. Patented Aug. 9, 1921.

Application filed November 17, 1920. Serial No. 424,645.

To all whom it may concern:

Be it known that we, JOHN W. OLIVER and HENRY BRUCKER, citizens of the United States, and residents, respectively, of the 5 city of New York, borough of Manhattan, in the county and State of New York, and Newark, in the county of Essex and State of New Jersey, have invented a new and Improved Thread Guide and Support, of 10 which the following is a full, clear, and exact description.

This invention relates to thread guides and supports, and has for an object the provision of a simple, efficient and economically 15 manufactured thread guide and support readily attachable to the hand of the person using it and in which the thread is led from the spool through the guide on the support in such a manner as to eliminate the tendency to unravel and snarl.

Another object of the invention is to provide a guide and support which is adapted to receive spools of thread wound in a variety of ways so that the operation of the 25 device is as efficient in one case as in another.

A further object resides in the particular construction and arrangement of parts hereinafter described and claimed and shown in 30 the accompanying drawings.

The invention is illustrated in the drawings, of which—

Figure 1 represents the hand of a person using the device, showing the device 35 mounted thereon;

Fig. 2 is a front elevation of the thread guide and support;

Fig. 3 is a side elevation thereof; and

Fig. 4 is a detail perspective view of the 40 guide through which the thread passes.

As illustrated in the drawings, the device is adapted to be attached to the wrist 1 of the person using it, and comprises a plurality of curved resilient spring metal 45 arms 2 adapted to embrace the wrist 1 and which are preferably integrally connected together by a strip portion 2'. To the upper surface of the connecting member 2' a plate of sheet metal, preferably aluminum, is attached in any suitable manner. This plate

50 3 is provided at each end with upwardly projecting, integrally connected portions 4.

A plate 5 is adapted be disposed across between corresponding edges of the vertical 55 portions 4 and is connected thereto by in-

wardly turned flange portions 6. The body portion 5 and the flange portion 6 may be made integral of one piece of metal which can be stamped in the form desired. Along the upper and the lower edges of the plate 60 5 between the vertical portions 4, a flange 7 is turned on the plate 5 to form between the flange and the body portion of the plate 5 a channel of any desired width in which an annular ring or washer 8 is adapted to 65 move back and forth. A slot 9 is formed in the plate 5, and the washer 8 is provided with an aperture 10. The inwardly turned portions or ears 6 are provided with apertures 11 adapted to be connected to the 70 vertical portions 4 by any suitable means, such as rivets. The upper ends of the vertical portions 4 are adapted to receive a shaft 12, one end of which may be adjustably connected to a snap fastener 13 of any suitable type whereby the shaft is adjustably disposed in position to receive a spool of 75 thread or other material 14 the free end 15 of which is adapted to pass, in the manner shown in Fig. 1, through the aperture 80 10 in the washer 8.

If, as in many cases, the thread is wound zigzag on the spool 14, the washer 8 will move back and forth in the channel formed by the flanges 7 so as always to be in the 85 line with the thread and yet efficiently guide the same.

It will be observed that the main body portion of our support and guide is formed of a small number of simply formed pieces 90 of sheet metal which can be very readily and economically manufactured and assembled. The spool 14 can be removed by merely removing the snap fastener 13 from the end of the shaft 12 which thereby can 95 be taken out of the vertical portions 4.

By making this device, preferably, of aluminum its weight is reduced to a minimum, and combined with simplicity and economy of manufacture, makes it an article 100 which is extremely useful and would appeal to a very large number of people.

It is evident that many modifications can be made in this device without departing from the spirit of the invention.

What we claim is:

1. A thread guide and support comprising a U-shaped integral body portion, a removable shaft extending between the outer ends of the legs of the U and adapted to re- 110

ceive a spool of thread, resilient gripping members attached to the lower face of the base of the U, a slotted plate disposed across between the leg members adjacent the 5 base of the U frame, flanges on said slotted plate attached to the leg members, integral overturned flange portions on the upper and lower edges of the plate adjacent the slot, and forming a channel, and a washer located in said channel and adapted loosely 10 to slide therein and guide the thread.

2. A thread guide adapted to be attached

to a spool-supporting frame which comprises a slotted plate, a perpendicular flange at each end of said plate, said flanges adapted to be attached to the frame, overturned flange portions at the upper and lower edges of the plate and extending adjacent the slot, and an annular shaped washer disposed in the channel formed by said overturned 20 flanges and adapted to receive a thread.

JOHN W. OLIVER.
HENRY BRUCKER.
